UNITED STATES PATENT OFFICE.

DAVID M. MONROE, OF BALTIMORE, MARYLAND.

CAN-SOLDERING MACHINE.

SPECIFICATION forming part of Letters Patent No. 293,346, dated February 12, 1884.

Application filed December 11, 1883. (No model.)

To all whom it may concern:

Be it known that I, DAVID M. MONROE, a citizen of the United States, residing at Baltimore city, in the county of Baltimore and State of Maryland, have invented certain new and useful Improvements in Can-Soldering Machines, of which the following is a specification, reference being had therein to the accompanying drawings.

10 My invention relates to improvements in can-soldering machines in which the side seams of sheet-metal cans are soldered; and the objects of my improvements are, first, to provide means whereby the outside of the 15 seamed bodies shall all measure alike; second, to adapt a single gaging device to a rotary conveyer, so that the bodies placed or gripped thereon may be sized by one gaging apparatus, which simplifies the machine, and the 20 soldering, being done, in the usual manner, by an operator with a hand-copper, at a point on the conveyer away from the gaging device, does not subject the same to the heat and flux therefrom; and, third, to provide mechanical 25 means whereby the several parts may be rapidly and accurately operated. I attain these objects by the mechanism illustrated in the accompanying drawings, in which—

Figure 1 is a side elevation of the machine; 30 Fig. 2, a top view of the same; Fig. 3, an enlarged view of the gaging device, part of which is in section; Fig. 4, top view of same; Figs. 5 to 13, views of the gaging-heads.

Similar letters refer to similar parts throughout the several views.

35 The top A and legs B constitute the frame of the machine, to which is attached a vertical shaft, C, on which a rotary conveyer, D, rotates, the latter having a vertical adjustment 40 by which it may be set to accommodate the different heights of the can-body-gaging device.

On the shaft C is a collar, a, which is held to its place by a set-screw, a', and to which is attached a pocket, a'', carrying within it a 45 spring and pin, a''. The spring, pressing on the pin a'', forces it into the notches b of the conveyer D, holding the same in its position while the can-body R is being gaged; but on exerting sufficient power to the conveyer D to 50 overcome the spring, it may be rotated to the

following notch, and so on, stopping and holding the same each time at its proper place.

On the several arms of the conveyer D are placed the can-body grippers or holders, which operate in conjunction with the gaging device, 55 and consist of downward and outward projecting arms c, to which is pivoted a lever, c', and attached to the outer end of same is a knife, c'', which is pressed to the arms c by means of the spring c' and rod c'', holding the 60 can-body R, when there placed, firmly to its proper size and position, while the soldering is being done, and until released therefrom. The lever c' and knife c'' are operated by the rock-arm i, pivoted at i' to the bearing E, (see 65 Fig. 1,) and projecting below the frame-top A, there connecting with a rod, i'', which extends under the frame-top to the end of same, and projecting therefrom, carrying a breast-plate, i''. On pressing the breast-plate i'' inward, the upper end of the rock-arm i will 70 bear down on the lever c', thereby raising the knife c'', allowing the can-body to be placed, adjusted, gaged, &c.

The heads F F consist, first, of semi-annular outside gages, d, provided with projecting flanges d', which project over the end of the can-body on the outside, permitting the can-body to be expanded only to a given diameter, 75 said diameter being changeable by means of 80 the slots f and screws f', which will permit the gages d to be moved inward or outward; second, of inside expanding-jaws, e, which are operated by the springs h, which draw the jaws e together, and the rod n, which forces them 85 apart, by having the end that engages with the jaws e V-shaped, which acts as a wedge when forced between them; and, third, a cross-head, t, to which the gages d and the expanding-jaws e are secured, the latter sliding in 90 dovetail grooves m, and the former in dovetail grooves m'. The cross-head t is attached to the shaft t', which is hollow, and through which the rod n moves, the whole having a reciprocating movement, which is imparted thereto from the 95 rock-arm k, which is pivoted at k', the upper end of same projecting through an elongated slot, s, in shaft t', and into a slot, s', in the rod n. On the outer end of the rod n is secured a 100 collar, n', which bears on the spring n'', the

other end of which bears on the shoulder t^2 in the shaft t' . By an inward movement of the arms k k , the shafts t t' and their attachments approach each other until the stops v on the shafts t t' come in contact with the bearings E , which prevents the shafts t t' moving farther forward. The rock-arms k continue to advance, and with them the rods n , the springs n^2 allowing the continued movement of the rods n , which expands the jaws e , thereby pressing the can-body R outward against the outside gage, d , always keeping the outside of the can-body the same size. The stops v are set to stop the heads F F at a point sufficiently apart to allow the can-body to enter the heads F F only a given distance, thereby preventing the same from injuring the ends of the can-body.

To the lower end of the rock-arms k is attached a connecting-rod, k^2 , which is attached to an equalizing-bar, q , provided with springs q' and guides q^2 . To the bar q is connected the treadle y by means of a rod, y' .

In working the above invention, if the gages d should wear, as in devices of like kind heretofore, the deficiency caused thereby may be obviated by moving the gages d inward, the slots f and screws f' permitting the same.

In operating the machine one man and a boy are required. The boy places the rolled blank on the arm of the conveyer—that is, between the gaging-heads—first raising the knife c^2 by pressing the breast-plate i^2 inward, then gaging the can-body by depressing the treadle y , and holding the same down until releasing the breast-plate i^2 , which permits the knife c^2 to clamp and hold the can-body on the arm of the conveyer D . The treadle y is then released, allowing the heads F F to draw back from the can-body. The conveyer is then rotated by the boy until the arm following comes between the gaging-heads. The operator or seamer solders the seam, in the usual manner, with a hand-copper, standing at right angles to the gaging device, in the direction therefrom in

which the conveyer rotates, thereby permitting the seamed bodies to move three-fourths the circle traveled by the conveyer D , allowing the seamed bodies ample time to cool, which are then removed by the boy at the gaging device.

Having fully described my invention, what I desire to claim and secure by Letters Patent is—

1. The combination of a rotary conveyer, D , having attached thereto projecting arms c and clamping-knives c^2 , and a gaging device provided with gages d , inside expanding-jaws, e e , and mechanism that will force the jaws e e apart, as set forth, and for the purpose as herein specified.

2. In a can-body-gaging device, the combination of two reciprocating heads, F F , provided with outside gages, d , inside expanding-jaws, e e , and mechanism to force the jaws e e apart, whereby each end of the can-body will be gaged at the same time.

3. The combination of the outside gages, d , inside expanding-jaws, e e , a reciprocating carrier or shaft, t' , attached thereto, and mechanism contained therein which will force apart the jaws e e when they cease to move in the direction of the can-body.

4. In a can-seaming machine, the combination of a conveyer having a vertical adjustment and a device to stop and hold the conveyer, whereby the conveyer may be adjusted vertically by the vertical adjustment of the stop and holder.

5. The combination of a reciprocating cross-head, t , adjustable gages d , expanding-jaws e , rod n , spring n^2 , and shaft or carrier t' , operated as set forth.

In testimony whereof I affix my signature in presence of two witnesses.

DAVID M. MONROE.
